CLAIM

The ornamental design for the fish scent dispenser, as shown and described.

DESCRIPTION

FIG. 1 is a perspective view of a fish scent dispenser showing my new design;

FIG. 2 is a top plan view thereof;

FIG. 3 is a bottom plan view thereof;

FIG. 4 is an end view thereof, the opposite end being identical thereto;

FIG. 5 is a perspective view of an alternate form of the present design;

FIG. 6 is a top plan view of the alternate form;

FIG. 7 is a bottom plan view of the alternate form;

FIG. 8 is an end view of the alternate form, the opposite end being identical thereto; and,

FIG. 9 is a sectional view taken along line 9—9 in FIG. 6, said section being identical to a section taken along line 9—9 in the embodiment of FIG. 2.
